(57) **CLAIM**

The ornamental design for an anti-tamper dispensing bottle holder, as shown and described.

DESCRIPTION

FIG. 1 is a front perspective view from above of an anti-tamper dispensing bottle holder showing our new design, in a locked position;

FIG. 2 is a rear perspective view from below thereof, in the locked position;

FIG. 3 is a front elevational view thereof, in the locked position;

FIG. 4 is a rear elevational view thereof, in the locked position;

FIG. 5 is a right side view thereof, in the locked position;

FIG. 6 is a left side view thereof, in the locked position;

FIG. 7 is a top plan view thereof, in the locked position;

FIG. 8 is a bottom plan view thereof, in the locked position;

FIG. 9 is a front perspective view from above thereof, in an unlocked position; and,

FIG. 10 is a further front perspective view from above thereof, in the unlocked position.

The broken lines showing the dispensing bottles are for the purpose of illustrating environment and form no part of the claimed design.

1 Claim, 10 Drawing Sheets
